UNITED STATES PATENT OFFICE.

WILLIAM E. SNEDIKER, OF TRENTON, NEW JERSEY.

MACHINERY FOR FORMING THE EYES OF PICKS AND OTHER TOOLS.

SPECIFICATION forming part of Letters Patent No. 268,955, dated December 12, 1882.

Application filed July 20, 1882. (No model.)

To all whom it may concern:

Be it known that I, WILLIAM E. SNEDIKER, of Trenton, in the county of Mercer and State of New Jersey, have invented a certain new and useful Improvement in Machines for Forming the Eyes of Picks and other Tools, of which the following is a specification.

My invention relates to the kind of machine which comprises a punch or punches and a die or dies composed of sections which are separable to permit of the withdrawal of the "eye" after it has been formed by the descending punch.

The invention consists in the combination, with a plunger and one or more punches carried thereby, of rigid and movable die-sections, a cam or cams adapted to be rotated alternately in reverse directions to hold and release the movable die-sections, a rotary shaft for operating said plunger, and mechanism for imparting to the cam or cams a rotary motion alternately in opposite directions from the aforesaid rotary shaft, to hold and release the movable die section or sections at the proper times.

In the accompanying drawings, Figure 1 represents a front elevation of a machine embodying my invention. Fig. 2 represents a side elevation thereof. Fig. 3 represents a horizontal section upon the dotted line $x-x$, Fig. 1, the punches being omitted; and Fig. 4 represents a plan, and Fig. 5 a side view, of the cams which I employ.

Similar letters of reference designate corresponding parts in all the figures.

A designates the bed-frame of the machine or press, and A' designates the side frames thereof.

B designates a plunger adapted to move vertically in guides a ; and C designates a shaft, mounted in bearings in the side frames, A', and adapted to be rotated by means of a counter-shaft, C', carrying a pinion, b, which engages with a wheel, c, on the shaft C.

The counter-shaft C' may be rotated by a belt passing over a pulley, d, thereon.

Upon the shaft C are two eccentrics, e, which operate the plunger B through rods e'; but, in lieu of eccentrics, cams or cranks may be employed.

The plunger B may carry one or more punches; but in this instance two punches, $f-f'$, are employed, and the metal is subjected to them both, one of them being a finishing-punch.

Upon the bed A are two dies, each composed of two sections, D D'. The sections D are secured rigidly to the bed by means of bolts g or otherwise; but the sections D' are only secured at one end by pivots g' , and are movable on said pivots toward and from the rigid sec-

tions. At the free end of each movable die-section D' is represented a projection, h , which slides laterally under an overhanging lip, h' , and the said lip prevents the movable section from being lifted as the punch recedes.

In the bed-frame A is mounted a shaft, E, having a gear-wheel, i, secured on its end; and j designates a rack adapted to be reciprocated in guides k , and engaging with said wheel i. The rack j is reciprocated by an eccentric, l, on the shaft C, and a rod, m, and by such reciprocation the shaft E is rotated alternately in opposite directions.

On the shaft E, between the two movable die-sections D', is secured a hub or cylinder, F, having on opposite sides two cams, n, which are adapted to act upon shoulders o on the movable die-sections D' as the shaft E is rotated, and so move the said die-sections into and hold them in proper relation to the rigid die-sections D while the punches are operating on the metal held between the die-sections. As the shaft E is turned backward or in a reverse direction the cams n release the movable die-sections D', and allow them to be drawn toward each other and away from their companion rigid section D by a spring, p.

The mechanism herein described for operating the movable die-sections is of course applicable whether one, two, or more punches and dies are employed in the machine, except that there should be one cam n for each movable die-section.

The arrangement of the cams n below or at the level of the bed is advantageous, because it leaves the whole space above the dies unobstructed when the plunger is raised.

What I claim as my invention, and desire to secure by Letters Patent, is—

1. The combination, with a plunger and one or more punches carried thereby, of rigid and movable die-sections, a cam or cams adapted to be rotated alternately in reverse directions to hold and release the movable die-sections, a rotary shaft for operating said plunger, and mechanism through which said rotary shaft imparts an alternate rotary motion to said cam or cams, substantially as described.
- 10 2. The combination of the bed A, the rigid

and pivoted die-sections D D', the plunger B, with punches ff' , the rotary shaft C, the eccentrics e or cams, and the rods e', the shaft E, the cams n, the pinion i, the rack j, the eccentric l, and the rod m, substantially as described. 15

W. E. SNEDIKER.
